DESIGN FOR A COMBINED TOBACCO TIN HOLDER AND ASH RECEIVER

Karl B. Weber III, Pittsburgh, Pa.

Application October 29, 1941, Serial No. 103,934

Term of patent 7 years

To all whom it may concern:

Be it known that I, Karl B. Weber III, a citizen of the United States, residing at Pittsburgh, in the county of Allegheny and State of Pennsylvania, have invented a new, original, and ornamental Design for a Combined Tobacco Tin Holder and Ash Receiver, of which the following is a specification, reference being had to the accompanying drawing, forming part thereof.

Figures 1, 2, and 3 are, respectively, top plan, front elevational, and side elevational views of a combined tobacco tin holder and ash receiver, showing my new design.

I claim:

The ornamental design for a combined tobacco tin holder and ash receiver, as shown.

KARL B. WEBER III.
